CONTAINER

Mitchel E. Holy, Posen, Ill., assignor to Container Corporation of America, Chicago, Ill., a corporation of Delaware

Application August 24, 1935, Serial No. 37,725

4 Claims. (Cl. 229—23)

This invention relates to containers adapted to be formed of paperboard and like material.

One object of the invention is to provide an effective but inexpensive container adapted to be collapsed to a flat condition for storage and shipment and capable of being readily set up.

Another object of the invention is to provide a container having a polygonal or multi-sided tubular body with cooperating top and bottom closures adapted to be readily assembled with the tubular body.

A further object of the invention is to provide a bottom closure which is provided with means cooperating with parts on the body member whereby the bottom closure, when assembled with the body member, will be securely held in place without necessitating the use of securing means other than the interlocking parts of the body and the bottom closure.

A still further object of the invention is to provide a top closure which may be readily assembled with the body of the container so as to be removably interlocked to the body member.

To these and other ends the invention resides in certain improvements and combinations of parts, all as will be hereinafter more fully described, the novel features being pointed out in the claims at the end of the specification.

In the drawing, showing a preferred embodiment of the invention, the figure is a perspective view of the container with the top and bottom closure members shown in their proper relative positions with respect to the body member but somewhat removed from the ends thereof.

The present invention, as illustrated, provides an inexpensive form of container for relatively light loads of small articles, such as, for example, individual ice cream cups or containers, where it is desired to facilitate the packaging as well as the dispensing of such small articles and at the same time avoid the use of separate closure securing means such as adhesive, gummed tape, rivets or staples.

The container in its preferred form is illustrated as comprising a tubular body portion 1, a bottom closure 2, and a top closure 3. The body portion and top and bottom closures are preferably constructed of suitable sheet material, such as light solid fibre board which can be readily scored or creased.

The tubular body member 1, for purposes of illustration, has been shown as having eight side walls indicated by numerals 4 to 11 inclusive.

It is, however, to be understood that the container may be formed of other polygonal shapes hav-

ing more than four sides of substantially equal width whereby the angles between the sides will be greater than right-angles. Containers having an even number of sides are preferably employed.

A glue flap 4a, as illustrated, is preferably provided to connect the walls 4 and 11 in a well known manner.

The alternate side walls of the body member 1 at both top and bottom are preferably provided with short flaps 12, 12 and 13, 13 which cooperate respectively with the tabs 14, 14 and 15, 15 on the lower and upper closure members 2 and 3.

The tabs 14, 14 and 15, 15 are formed somewhat similar to each other except that the tabs 14, 14 are formed to provide a substantially permanent connection between the bottom closure 2 and the body member, while the tabs 15, 15 are formed to provide a readily releasable connection between the top closure 3 and the body member.

For the purpose of securing the bottom closure 2 to the body member 1, the tabs 14, 14 are formed with lateral extensions 16, 16 defined from the main tab portion by crease lines 17, 17 so that the tab extensions 16, 16 may be bent over at an angle to the face of the tab 14 when it is desired to insert the tab 14 between two adjacent flaps 12, 12. When the tab 14 is thus inserted the extensions 16, 16 thereon will spring back and engage over the upper surfaces of the flaps 12, 12, 30 these flaps having been bent to extend inwardly when the tubular body member is set up. After all of the tabs 14, 14 have been inserted between adjacent flaps 12, 12 in the manner just described it will be apparent that the tab extensions 16, 16 by engaging on the upper surfaces of the flaps 12, 12, will cause the tabs to be securely locked with such flaps and the tabs may be removed intact only by very carefully bending the extensions 16, 16 from their positions over the flaps 12, 12.

It is not necessary that each of the tabs 14, 14 be provided with the score lines 17, 17 between the tab proper and the extensions 16, 16. The majority of these tabs, however, are preferably so constructed to facilitate ready insertion of the tabs between the flaps 12, 12 in their bent-over positions to thus securely lock the bottom closure 2 to the tubular body member.

While the flaps 13, 13 are preferably of a width substantially equal to the width of their attached side walls, and the tabs 14, 14 with the extensions thereon have an over-all width somewhat greater than the edges of the closure member to which they are attached, these widths

may be somewhat varied, it being essential, however, that the over-all width of tabs 14, 14 is somewhat greater than the maximum spacing between the adjacent flaps 13, 13 so that the extensions 16, 16 will overlap the flaps 12, 12 as previously explained.

In order to facilitate the insertion of the tabs 14, 14 between adjacent flaps 12, 12 the crease lines 17, 17 in the tabs 14, 14 are preferably inclined so as to converge outwardly of the tab thus giving the tab a tapered shape. The tab extensions 16, 16 are also preferably cut so as to be tapered toward the outer edge of the tab 14.

As above stated, the top closure is so formed as to permit it to be releasably secured to the tubular body member. For this purpose the tabs 15, 15 are somewhat widened as indicated at 19, 19 closely adjacent the juncture of the tab with the edge of the top closure 3 so as to provide shoulder portions 20, 20 which are adapted to engage beneath the underside of the inturned flaps 13, 13. The distance between the extremities of the shoulder portions on tabs 15, 15 is slightly greater than the maximum spacing between adjacent flaps 13, 13 on the body member. In pressing the tab 15 into the space between the edges of flaps 13, 13 there will be a slight deformation of the material at the extremities of the shoulders 20, 20 as well as the edges of the flaps 13, 13 which are contacted by these shoulders 20, 20. The tendency of the material, such as fibre board, to regain substantially its original shape after such distortion will cause the shoulders 20, 20 to rather firmly engage the flaps thus releasably locking the top closure 3 to the body member.

The tabs 15, 15 are preferably provided with tapered edges 21, 21 to facilitate insertion of the tabs between adjacent flaps 13, 13.

In the utilization of the container of the present invention the tubular body member will be collapsed to flat condition for shipment and, when it is desired to set up the container, it is only necessary to expand the body member and fold over the flaps 12, 12 at the bottom of the body member. The bottom closure may then be secured in place by folding upward the tabs 14, 14 and 16, 16; then inserting the tabs between the flaps 12, 12 so that the tab extensions 16 will engage on the upper surfaces of these flaps. The container may then be filled with merchandise after which the top closure 3 will be assembled on the top of the body member by a similar operation.

From the foregoing it is apparent that the present invention provides a simple and effective container which may be retained in flat condition until ready for use and which can be assembled without the use of special equipment and with a minimum of hand manipulation. The provision of short, interengaging flaps tends to greatly eliminate waste which occurs in the construction of many forms of containers, due to the fact that overlapping flaps are employed. By so forming the container as to provide short interlocking flaps and tabs, it is thus possible to form the container with only a negligible amount of material being wasted in the blanking operation. For lightweight edible merchandise, such as small ice cream containers, lightweight candies and similar goods, the present container is quite advantageous as it can be readily set up, packed and

sealed, and, due to the convenient form of cover, the retailer is enabled to keep the contents of the container free from dust and dirt as the top closure may be easily removed and then replaced on the container. When the container is empty, it may, if desired, be collapsed flat for reuse by carefully removing the bottom, as previously explained, or the container may be readily discarded as waste paper. While the present description sets forth a preferred embodiment of the invention, certain changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A box member consisting of a polygonal bottom part with tabs on alternate sides and a side part in the form of a continuous band with creases dividing it into panels equal in number and width to the sides of said bottom part, said side part having tabs at the bottom of alternate panels, said bottom part tabs being wider than the panels and having the portions that extend past their panel narrow enough to admit the side tabs between them and the body portion of the bottom part. 20

2. A box member consisting of a bottom piece in the form of a many-sided polygon with an even number of sides and tabs on alternate sides and a side piece in the form of a continuous band with creases dividing it into panels equal in number and width to the sides of said bottom piece and having tabs on alternate panels, the bottom piece tabs being wider than the panels and creased transversely along converging lines at the corners of the polygon, the inner edge of the portions of the bottom piece tabs beyond the creases being spaced outwardly and the side piece tabs fitting between the bottom piece tabs and the body portion of the bottom piece. 35

3. A box member consisting of an end piece in the form of a many-sided polygon with an even number of sides and tabs on alternate sides and a side piece in the form of a continuous band with creases dividing it into panels equal in number and width to the sides of said end piece and having tabs on alternate panels, the end piece tabs being wider than the panels and having notches in their inner margins at the corners of the polygon, and the side tabs fitting in said notches. 45

4. A box member consisting of an end piece in the form of a polygon with tabs spaced apart along the sides thereof and a side piece in the form of a continuous band with creases dividing it into panels equal in number and width to the sides of said end piece and having tabs alternating with said first-mentioned tabs, the end piece tabs being wider than the side piece tabs and having notches in their inner margins separating the bodies of the end piece tabs from the geometrical periphery of the polygon, and the side tabs fitting in said notches, said end tabs decreasing in width to the ends thereof so as to flex readily without being creased. 60
